Primary Examiner — Cathron C Brooks*Assistant Examiner* — Samantha Q Lawrence(74) *Attorney, Agent, or Firm* — Garvey, Smith & Nehrbass, Patent Attorneys, L.L.C.; Seth M. Nehrbass; Julie R. Chauvin(57) **CLAIM**

The ornamental design for a fire starter lance, as shown and described.

DESCRIPTION

FIG. 1 is a bottom view of a first embodiment, showing the design of a fire starter lance;

FIG. 2 is a top view of a first embodiment;

FIG. 3 is a left side view of a first embodiment;

FIG. 4 is a right side view of a first embodiment;

FIG. 5 is a front end view of a first embodiment;

FIG. 6 is a rear end view of a first embodiment;

FIG. 7 is a bottom view of a second embodiment, showing the design of a fire starter lance;

FIG. 8 is a top view of a second embodiment;

FIG. 9 is a left side view of a second embodiment;

FIG. 10 is a right side view of a second embodiment;

FIG. 11 is a front end view of a second embodiment; and,

FIG. 12 is a rear end view of a second embodiment.

No color is claimed as part of the design. The fittings shown in dotted or broken lines in FIGS. 1-12 are connectors and form no part of the claimed design.
